UNITED STATES PATENT OFFICE

FRED BOENIG AND GEORGE H. DRESSER, OF JAMAICA, NEW YORK

SMOKER'S MOUTHPIECE

Application filed May 13, 1929. Serial No. 362,792.

This invention appertains to improvements in appliances for smokers, and more particularly to a novel mouthpiece for holding cigars or cigarettes.

5 Although the present device is especially adapted for cigarettes, the same may be slightly modified to accommodate cigars without departing from the spirit and scope of the invention as claimed hereinafter.

10 The principal object of the invention is to provide a smoker's mouthpiece which will in use prevent the dropping of ashes on the clothes of the user, or persons nearby, without in any material degree affecting the proper draftline through the mouth piece and cigarette.

Another important object of the invention is to provide a mouthpiece wherein means is provided to prevent the burning of the user's 20 fingers, when the cigarette is burning close to its butt end.

Still another salient object of the invention, is to provide an ash guard and spark arrester for smoker's mouthpieces, which is 25 of dual construction, to more efficiently arrest the passage of inflamed particles.

These and numerous other important objects of the invention will become more apparent to the reader after considering the 30 invention as described and claimed herein-after.

In the drawings:

Figure 1 represents a side elevation of the novel mouthpiece.

35 Fig. 2 represents a fragmentary longitudinal sectional view through the novel device.

Fig. 3 represents a cross sectional view of the guard taken substantially on the line 3—3 of Fig. 1, and looking in the direction of the 40 arrow.

Referring to the drawings, wherein like numerals designate like parts, it will be seen that the invention includes a body 5 tapering toward one end, which end is provided

45 with the enlargement 6 for engagement by the user's teeth. As is shown in Fig. 2, the body is provided with a longitudinally extending smoker duct 7 and a pocket 8 at the end opposite from the enlargement 6. At the 50 pocketed end of the body external threads

are provided for engagement with the internal threads of the cylindrical fitting 9. The fitting 9 has a circumferentially extending shoulder 10 thereon and an annulus 11 coaxial with respect to the fitting 9 and of substantially the same diameter.

55 A pair of cylindrical guards 12 and 13, are provided, the guard 13 being of less diameter than the guard 12, and adapted to be enveloped by the larger guard 12. The guard 12, has one end secured to the periphery of the shoulder 10, while the adjacent end of the guard 13 is secured to the periphery of the annulus 11.

60 The remaining ends of the guards 12 and 13 are closed by a foraminous disk 14 of substantially the same material, of which the guards 12 and 13 are constructed. The disk 14 is secured to the end of the guard by soldering or some other suitable means or 70 method.

65 The numeral 15 denotes a cigarette with its butt end engaged within the pocket 8 and extending outwardly within the inner guard 13. As the cigarette burns inwardly, the fitting 9 will obviously become warmer, until when the cigarette has burnt closely to its but end, the heating of the fitting 9 may become quite warm. Insulation, in the form of a sleeve 16 of fiber or some other suitable 75 heat non-conductor is disposed in circumscribing position on the cylindrical fitting 9 in the manner shown clearly in Fig. 2.

80 It will thus be seen that by unscrewing the body 5 from the fitting 9, a cigarette may be inserted or removed from the pocket 8. The double guard serves to efficiently arrest any inflamed particles of the cigarette, and while the foregoing description has been in definite terms, it is to be understood that changes 90 may be made in the specific shape, size, and materials, without departing from the spirit and scope of the invention as claimed herein-after.

Having thus described our invention, what 95 we claim as new is:—

In a cigarette holder, a tubular member having an external annular shoulder between the ends thereof, an outer reticulated tubular guard receiving said annular shoulder and 100

secured to the periphery thereof, an inner reticulated guard within said outer guard and secured on said tubular member in advance of said annular shoulder, a mouth piece detachably threaded into said tubular member and having means for supporting a cigarette, and a band of insulating material secured on said tubular member rearward of said annular shoulder and in contact therewith.

¹⁸ In testimony whereof we affix our signatures.

FRED BOENIG.
GEORGE H. DRESSER.
